UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE-CHANNELING MACHINE.

Application filed June 7, 1919. Serial No. 302,576.

To all whom it may concern:

Be it known that I, FREDERIC E. BERTRAND, a citizen of the United States, residing at Lynn, in the county of Essex and State of Massachusetts, have invented certain new and useful Improvements in Sole-Channeling Machines; and I do hereby declare the following to be a full, clear, and exact description of the invention, such as will enable others skilled in the art to which it appertains to make and use the same.

This invention relates to stock fitting machines and more particularly to such machines for channeling soles for use in the manufacture of turn boots and shoes.

The prevailing style in shoemaking at the present time demands the use of lasts having extremely pointed toes and this style is especially prevalent in turn shoes. To build a shoe on these narrow toed lasts it is necessary to shape the sole with a much more pointed toe than has generally been in use, such soles being known to the trade as "peaked-toe" soles. Much difficulty has been experienced in inseaming the shoes in which these soles are incorporated due to the fact that the operator of the inseaming machine is not permitted, by reason of the narrow space at the extreme point of the toe, to sew down the advance side of the toe with stitches that are inserted, as they should be, at right angles to the line of feed. Consequently, in order to give more room for the strokes of the awl and the needle the shoe is swung somewhat before it should be. As a result the stitches are distorted and the between substance weakened to such an extent that the shoe rips at the toe, frequently before its completion, causing a cripple. This is particularly true in making turn shoes. In this type of shoe the step of turning it right side out places a severe strain on the inseam at the toe, which if it is not well made will rip.

The object of the present invention is to produce a sole which can be incorporated in shoes of the prevailing pointed toe style and securely fastened to the upper about the toe, thus avoiding the production of cripples from the cause hereinbefore alluded to.

In accordance with this object a feature of the invention comprises the provision of means in a sole fitting machine which will

enable the operator to produce a higher shoulder about the end of the toe than is requisite along the shank and sides of the fore part. Such a shoulder at the toe will give a sufficient backing to the upper materials to permit of stapling the upper to the sole about the toe; it being the purpose of this invention to produce a sole which will permit of an elimination of the usual sewed inseam at the toe thus effectually preventing the production of a cripple by an insecure inseam at this part of the shoe. Accordingly the sole fitting, or channeling, machine is provided with tools which will produce on the sole the usual edge fitting, i. e., a shoulder for turn sole and women's welt insole work, along the shank and sides of the fore part, and a lip about the end of the toe which, when raised, affords the higher shoulder required for the stapling operation. Preferably the machine will be provided with two edge knives, one for slitting the edge to form a lip, and the other for cutting a shoulder, both operating on the same portion of the sole, i. e., the margin outside the between substance, the lip knife being in advance of the shoulder knife, so that while both are in operative position a shoulder alone is produced. Provision is made for raising the shoulder knife on approaching the toe on one side and then dropping it in position again after rounding the toe, thus producing a lip alone about the toe.

To the accomplishment of this object and such others as may hereinafter appear, as will be readily understood by those skilled in the art, the invention comprises the features and combinations of parts hereinafter described and particularly pointed out in the appended claims.

In the accompanying drawings showing the preferred form of the invention, Figure 1 is a rear elevation of a Goodyear Universal channeling machine (turn work) fitted with the new knives for producing a lip at the toe of a shouldered sole. In this view both the shoulder and edge slitting knives are shown in operative position, their combined operation forming a shoulder; Fig. 2 is an enlarged detail of the operating tools and connecting parts showing the shoulder knife raised and a lip alone being formed; Fig. 3 is a plan, partly in section, of the parts

shown in Fig. 2; Fig. 4 is an end elevation showing the edge knives both in operative position, the operating instrumentalities being shown in the relative positions assumed just prior to starting a feed stroke. In this view the channel knife block with its knife is removed; Fig. 5 is an exploded view, in perspective, of the knife block which carries the edge slitting 5 and shoulder knives; and Fig. 6 is a view, in perspective, of the toe end of a sole produced by the machine.

The illustrated embodiment of the invention shows the present commercial Good-15 year Universal channeling machine for making turn soles, except in the particulars described in detail hereinafter, the head frame 10 of which supports the work engaging instrumentalities. These include a 20 work support 12, above which is mounted the oscillating knife carrier 14 driven by connections, including a link 16 (Fig. 4), between said carrier and an eccentric 17 on the main shaft 18, which is rotated by a 25 belt running over the pulley 20. Within the oscillating carrier 14 are the vertically yielding slides 22 and 24 for the edge knife and channel knife respectively, these two slides being held downward by the springs shown 30 within the head 26 in Fig. 1. Also supported by the oscillating carrier is a way carrying the slide 28, to which is connected the downwardly projecting arm 30 having secured to its lower end the edge pressure gage 35 32. The gage 32 is held yieldingly downward by a spring 34. The channel knife slide 24 is provided with a portion 36 (Fig. 4) at its lower end which projects outwardly 40 from the oscillating carrier and supports the channel knife pressure gage 40. When the work is fed across the work table 12, the oscillating carrier moves the sole forward on its forward stroke by the pressure of the 45 gages 32 and 40 upon it, but the sole is held from movement on the rearward stroke of the carrier by means of the presser foot 42 sustained at the lower end of a spring 44 and given a vertically reciprocatory movement by suitable connections with an eccentric 46 on the forward 50 end of the shaft 18.

All of the parts thus far described, with the exception of the particular shape of the 55 edge pressure gage arm 30 and of the channel knife carrier 38, may be, and preferably are the same as illustrated and described in the present inventor's prior Letters Patent of the United States Nos. 1,030,704 and 1,030,710, both dated June 25, 1912.

The arm 30 which sustains the edge pressure gage 32 is of the formation illustrated 60 in Figs. 2 and 4, rather than as shown in said prior patents, because of the new construction and arrangement of the edge knife block to be hereinafter described. The chan-

nel knife carrier 38, it will be observed, is so formed as to support a channel knife 48 so shaped that in order to perform its function it must be positioned with its shank arranged vertically with respect to the plane 70 of the work table instead of obliquely thereto as illustrated in said prior patents. The purpose of this shape of channel knife is more particularly for peaked-toe work, since it has been found that the obliquely ar- 75 ranged knife interferes with the turning at the toe on soles of this style because of the small amount of room at the toe allowed by the rapidly converging sides of the sole. The vertical shank on the channel knife and the 80 simplified holder therefor, as will be recognized by those skilled in the art, permit an easy turning of the peaked-toe soles without interference. This change forms no part 85 of the present invention.

The work table 12 is lowered in order to insert and remove the work by means of a treadle connected to the treadle rod 50, a depression of which first breaks the toggle 52 and then lowers the table. It is desirable that the channel knife 48 be elevated at the same time the table is lowered, and therefore the toggle 52 is connected by an arm 53, bell crank 54 mounted on a pivot pin 55, and intermediate links 56 and 57 to a horizontal arm 58 loosely pivoted on the rock-shaft 60 at the top of the head frame 10. The arm 58 carries a screw 59 which bears upon a lever 61, also loosely mounted upon said rock-shaft 60 and extending under a pin 62 projecting laterally from the slide 24 which carries the channel knife. An inspection of Fig. 1 will show that through these connections the lowering of 95 the work table will simultaneously raise the channel knife. On releasing the treadle 100 these parts are returned to their operative positions by springs provided for this purpose.

The feature just described is fully illustrated and claimed in the inventor's prior Letters Patent of the United States No. 1,023,801, dated April 23, 1912, but the pivot pin 55 and the rock-shaft 60 are employed 115 in the novel mechanism now to be described.

The instrumentalities for operating on the margin of the sole opposite the channel knife and outside the between substance are not shown, in the combination herein illustrated, in any of the prior patents. The edge knife block as in said prior patents referred to, is mounted upon the lower end of the edge knife slide 22, but it is made in two parts 120 64 and 66 as shown best in Fig. 5 which support a shoulder knife and an edge slitting knife respectively. These two parts, although separable, are removable from the machine as an entirety. The parts 66 is provided with a vertical channel which 125 embraces the lower end of the slide 22 and 130

opposite this channel it has a tongue which fits into a complementary recess in the part 64 (see Fig. 5), the part 64 being provided with a guide pin 65 which projects into a hole in the part 66 and thus determines the proper relation of the two parts when they are brought together. Elongated bolt holes 67 and 68 are provided in the parts 64 and 66 respectively, and the two parts when assembled together are held on the slide 22 by a bolt 69 passed through the holes and threaded into the slide. The vertical position of the edge knife block is determined by the vertical position of the adjusting screw 70, the head of which engages a slot 71 in the part 64 upon the same principle as is disclosed in the inventor's prior Letters Patent of the United States No. 1,030,703, dated June 25, 1912.

The edge knife block is made in two parts so that it may be provided with holders for two relatively movable knives instead of one knife only as heretofore. The part 66 is provided with a fixed holder 72 for an edge slitting knife 74. The part 64 is provided with a vertical dovetailed way 76 for a dovetailed slide 78 which sustains a holder 80 for a shoulder knife 82. The slide 78 which carries the shoulder knife 82 is permitted a vertical movement within the way 76, but is normally held in its lower position with the shoulder knife in operative position by means of an expansion spring 84, the upper end of which bears against the head of an adjusting screw 86, threaded through a lug on the part 64 and the lower end of which bears against the upper side of the central portion of a lever 88 one end of which is pivoted on the part 64. The lever 88 is provided with an inwardly projecting pin 90 which passes through a vertically elongated hole 91 in the part 64 and into a horizontally elongated hole 92 in the shoulder knife holder slide 78. When the slide 78 is in its lower position, the lever 88 rests upon an adjustable screw 94 (Fig. 1) the position of which controls the vertical relation of the two knives to each other and which is manipulated as may be required to properly maintain this relation.

The vertical movement of the slide 78 within the part 64 of the edge knife block is under control of the operator. The lever 88 is provided on its free end with a head 96 which overlies the free end of a vertically movable lever arm 98 pivoted at its other end upon the pivot pin 55. A link 100 connects the arm 98 with one end of a substantially parallel lever arm 102, the other end of which is fixed to the rear end of the rock-shaft 60. At the front of the machine the forward end of the rock-shaft 60 has another lever arm 104 secured thereto, and a depending link 106 connects this

lever arm to an operating handle 108 loosely pivoted upon a horizontal pin 110 carried by a bracket 112 secured to the head frame 10. The lever arm 104 is held lifted by means of an expansion spring 114, at the front of the machine, located between the under side of the lever and a lug 115 projecting from the head frame 10, and surrounding a rod 116, which passes through both the lever arm and the lug and is secured in position by suitable nuts. A suitable adjustment of the rod 116 acts to maintain the free end of the lever 98 a short distance below the head 96 of the lever 88 and thus provides the clearance necessitated because of the arcuate movement imparted to the head 96 by the oscillating knife carrier 14.

In operating the machine the table is lowered and the sole entered, its edge resting against the usual edge gage 118 (Fig. 1) and at this time the slide 78 which carries the shoulder knife 82 is in its lower position locating this knife just in the rear of the edge slitting knife 74, so that when the cutting edge 75 of the knife 74 makes its edge slit as the sole is fed through the machine, the feather cutting edge 81 on the shoulder knife 82 will follow in exactly the same horizontal plane. The end of the shoulder knife cutting edge 81 is in alignment with the end of the slitting knife cutting edge 75, but the blade on which the edge 81 is formed extends above the blade of the slitting knife, the angle between these two blades being about two degrees. This prevents the shoulder knife from digging in and spoiling the margin, the feather being formed by the slitting knife alone.

The shoulder knife 82 has one peculiarity over the usual shoulder knives in that it has a distinct shoulder forming blade which extends forwardly of the feather cutting edge 81. This blade is provided with a shoulder cutting edge 83 in advance of its feather cutting edge and located adjacent the end of the edge slitting knife 74. The edge 83 projects forwardly and upwardly from the outer end of the edge 81 and functions to hold down the sole as the string is severed, thus producing a sharply defined shoulder. (See Fig. 4).

Now then, on the sole being fed through the machine from the shank toward the toe, the channel knife 48 performs its usual function and the knives 74 and 82 act together to first form an edge lip and then cut away the lip thus produced, leaving the usual shoulder required on turn soles, and on welt insoles for women's work (see Fig. 1). At about one and one-half inches in the rear of the tip of the toe, however, or about opposite what would be the end of the tip line of the upper when the shoe is assembled, the operating handle 108 is de-

pressed. This raises the lever arm 98 which, by engaging the head 96 of the lever 88, elevates this latter lever and with it the slide 78 which carries the shoulder knife 82. This vertical movement of the shoulder knife relative to the edge slitting knife 74 causes its feather cutting edge 81 to cut transversely through the string which has been formed by the action of the two knives 10 and wholly sever it from the margin of the sole (see Fig. 2). The shoulder knife 82 now being in the position shown in Fig. 2, it can perform no operation upon the sole until again lowered into its former position. 15 Therefore, so long as the operator maintains the operating handle 108 depressed, a lip, instead of a shoulder, will be produced on the margin of the sole parallel to the channel made by the knife 48. But 20 after the toe has been swung and the knives are traveling toward the shank on the second side of the sole, the shoulder knife 82, by releasing the handle 108, is again dropped into position when opposite the point where 25 it was removed. On its downward stroke the edge 81 cuts transversely through the lip formed by the knife 74 and thereafter the two knives produce a marginal shoulder as before instead of a lip. The result of 30 the operations just described is shown by Fig. 6.

Especial attention is called to the means employed for adjusting the wear gib 120 in the way 76 (Fig. 5). As best shown in 35 Fig. 3 the outer side of this gib is engaged by cone shaped heads 121 on adjusting bolts 122 which are seated in suitably shaped recesses formed therefor in the inner face of the edge knife block part 64. As the gib 40 wears it is adjusted by tightening the nuts on the bolts 122 thus drawing the head 121 forward and wedging the gib 120 inward. With this construction the adjusting screws are in a readily accessible position at the 45 rear of the machine as shown in Figs. 2 and 3.

While it is preferred to employ the specific construction and arrangement of the parts shown and described, since this 50 construction and arrangement is the simplest and most efficient embodiment of the invention which has yet been devised, it will be understood that this construction and arrangement is not essential except so far as 55 it is specified in the claims, and may be varied or modified without departing from the broader features of the invention.

What is claimed as new, is:—

60 1. A sole channeling machine having, in combination, work supporting and feeding means, and means for forming a shoulder along a portion of the edge of the sole and a lip in continuation thereof along another portion of said edge.

65 2. A sole channeling machine having, in

combination, means for forming a marginal channel in the sole, and means for forming a shoulder parallel to a portion of said channel and a lip parallel to another portion of said channel.

70 3. A sole channeling machine having, in combination, a knife for slitting horizontally the edge of a sole, a knife to co-operate therewith by removing a string of waste to form a shoulder on the edge, both operating upon the marginal portion of the shank, and means for withdrawing one of said knives from operative position at the will of the operator.

75 4. A stock-treating machine having, in combination, a channel knife, an edge knife and a shoulder knife, said edge and shoulder knives operating on the same portion of the stock, the former in advance of the latter.

80 5. A stock-treating machine having, in combination, a work support at one side of the stock, a knife for slitting the edge of the stock, a cutter to co-operate in removing waste stock to form a shoulder and operating at the other side of the stock, and means for moving the cutter away from the work support during the operation of the machine while the edge slitting knife remains in 85 operative position.

90 6. A sole channeling machine having, in combination, an edge slitting knife to form a lip, a knife in the rear of said edge knife having an edge to sever the lip from its attachment to the sole and an edge to sever the string thus produced, and means to move said knife in a direction to sever said string.

95 7. A sole channeling machine having, in combination, cutting means for forming a channel, and simultaneously acting cutting means constructed and arranged to form an edge cut producing a shoulder in part and a lip in part.

100 8. In a sole channeling machine an edge cutter comprising co-operating cutting parts and means relatively to move them to produce a shoulder at the shank and sides of the forepart and a lip about the toe of a sole.

105 9. In a channeling machine, a channel knife, a knife for removing a strip of waste to form a shoulder and a knife to slit the edge of a piece of work to form a lip, said last two knives being opposite the channel knife and being arranged to be used alternatively.

110 10. In a sole channeling machine, a lip slitting knife and a shoulder knife, the former in advance of the latter, and means for discontinuing the operation of the shoulder knife while the lip slitting knife remains in operation.

115 11. A sole channeling machine having, in combination, a channeling knife, an edge slitting knife and a shoulder knife, said last two knives being opposite the channeling

knife and so constructed and arranged that while the slitting knife is in advance of the shoulder knife the shoulder cutting edge of the latter is at the end of the slitting edge 5 of the former.

12. In a sole channeling machine, an edge knife block containing two separable parts, one of which is provided with a fixed edge slitting knife holder and the other of which 10 is provided with a vertically movable shoulder knife holder.

13. In a sole channeling machine, an edge knife block provided with two holders for an edge slitting and shoulder knife, the 15 latter knife being at the heel of the former

and having its shoulder forming blade extending forwardly across the end of the former.

14. In a sole channeling machine, a shoulder knife having distinct feather forming 20 and shoulder forming blades, the latter blade extending forwardly in advance of the cutting edge of the former blade.

15. In a sole channeling machine, a shoulder knife having its shoulder cutting edge 25 in advance of its feather cutting edge, said shoulder cutting edge projecting forwardly and upwardly from the end of said feather cutting edge.

FREDERIC E. BERTRAND.
